(57) **CLAIM**

The ornamental design for a set of sound holes for stringed instrument, as shown and described.

DESCRIPTION

1. Set of sound holes for stringed instrument

1.1 : Front, top, and right side perspective view

1.2 : Front, bottom, and left side perspective view

1.3 : Enlarged view

1.4 : Enlarged view

1.5 : Front view

1.6 : Top view

1.7 : Bottom view

1.8 : Back view

1.9 : Right view

1.10 : Left view

1.11 : Enlarged view

1.12 : Enlarged view

1.13 : Enlarged view

1.14 : Enlarged view

1.15 : Enlarged cross-sectional view taken along line 1.15-1.15 in Fig. 1.7

1.16 : Enlarged cross-sectional view taken along line 1.16-1.16 in Fig. 1.7

The evenly-spaced broken lines in the drawings form no part of the claimed design; the dash-dotted lines in the drawings denote the boundary of the claimed design and form no part thereof; fig. 1.3 is an enlarged view of fig. 1.1 showing the
